CAT LITTER BOX

Robert W. Sleith, Wilbraham, Mass., assignor to Suburban Plastics, Inc., Three Rivers, Mass., a corporation of Massachusetts

Filed Aug. 4, 1969, Ser. No. 18,526

Term of patent 14 years

Int. Cl. D30—99

U.S. Cl. D30—99

FIG. 1 is a top left perspective view of a cat litter box showing my new design;

FIG. 2 is a right end elevation view of the cat litter box of FIG. 1;

FIG. 3 is a rear elevation view of the cat litter box of FIG. 1;

FIG. 4 is a bottom plan view of the cat litter box of FIG. 1; and

FIG. 5 is a front elevation view of the cat litter box of FIG. 1.

I claim:

The ornamental design for a cat litter box, as shown and described.
